(57) **CLAIM**

The ornamental design for display screen with animated graphical user interface, as shown and described.

DESCRIPTION

1.1: Front view of a first image;

1.2: Front view of a second image;

The broken lines showing a display screen and elements of the graphical user interface illustrate portions of the article and form no part of the claimed design. The appearance of the animated graphical user interface transitions sequentially between reproductions 1.1 and 1.2. The process or period in which one image transitions to another forms no part of the claimed design.
